LAUNDRY APPARATUS HAVING HEATER,
HOLLOW AGITATOR, AND SQUEEZER EX-
TRACTOR

Hill David Richardson, Houston, Tex.

Application September 14, 1951, Serial No. 246,691

3 Claims. (Cl. 68—15)

1

This invention relates to improved means for and methods of washing and drying fabrics and dishes, and more particularly to improved washing and drying processes and machines.

An object of this invention is to provide improved means for washing clothes and other fabrics, and dishes and kitchen ware.

Another object of this invention is to provide improved means for extracting soap, dirt, water and other liquids from clothes.

Yet another object is to provide a new and more economical means for rinsing clothes.

Still another object of this invention is to provide improved means for drying clothes, dishes and kitchen ware.

Other objects will appear more fully from the following description and accompanying drawings wherein:

Figure 1 is a schematic view in section of one embodiment of the apparatus which constitutes the invention, and which can be used to illustrate the processes of the invention.

Figure 2 is a detail in section of one portion of the apparatus illustrated in Figure 1 showing a cylindrical valve sleeve in an open position.

In one preferred embodiment of the invention illustrated, there is a conventional washing machine tub 1 fitted with an airtight lid or top 2 and a bottom drain and valve 3. The drain valve 3 is adapted to be connected to a waste or sewer line (not shown).

The tub 1 is also fitted with an oscillating agitator 4 comprising a vertical shaft 4a, carrying a circular disc 4b with perforations 4c therein, and flanges 4d rigidly secured on the top of the disc 4b and radiating from the shaft 4a.

In one preferred embodiment the shaft 4a is hollow with openings 6 at the top thereof. The openings 6 are so positioned with respect to the top 2, and the top 2 is so shaped, that water emitting from the openings 6 will splash against the top 2 and spray clothes which are in the tub from the top, thereby effecting a quick and thorough wetting of the clothes and solving the problem of floating dry clothes.

The shaft 4a is further provided with cylindrical valve openings or ports 8 at the bottom of the tub which, when open, will pass either fresh or drain water. A cylindrical sleeve 10 is fitted within the shaft 4a and extends with the shaft through the bottom of the tub. The cylindrical sleeve 10 may be moved vertically within the shaft 4a by a gear and rack 12 to which it is attached. When the sleeve 10 is in the up position, illustrated in Figure 1, the ports 8 are

2

closed; when it is in the down position illustrated in Figure 2, the ports 8 are open. In either position slots 14 in the lower portion thereof are opposite holes 16 in the lower portion of shaft 4a so that fluid inside the sleeve 10 may pass out through the shaft 4a into an annular space 18 formed around the lower extremity of the shaft 4a by an annular collar 20. The annular space 18 is connected by piping to other apparatus to be described hereinafter.

Also on the lower half of the shaft 4a, there may conveniently be fitted external gear teeth 22 which engage a pinion 24. The pinion is driven with an oscillating motion by a washing machine motor (not shown), and thereby causes the agitator 4 to oscillate.

Conveniently, a heater element 26 may be provided in the base of tub 1 to adjust automatically, for ideal temperature. The heater 26 and the disc 4b of the agitator may be of such size and may be so positioned in close proximity to each other as to prevent clothes from coming in direct contact with the heater 26. In the interest of simplifying the readability of certain details, the schematic drawing of Figures 1 and 2 have not been drawn to illustrate this.

Means may also be provided for squeezing clothes in the machine under positive compressive pressure. In the preferred embodiment illustrated a flexible tub 28 is used, being secured around the edges of the opening at the top of the outside tub 1, and being secured also at the bottom of the outside tub 1 just outside the drain 3 and the heater 26. An airtight annular space or between-tubs chamber 29 is formed by the sides of the two tubs, the wash chamber 30 being inside the flexible tub 28.

Packing is, of course, provided between the outside tub 1 and the shaft 4a to prevent water leakage from the tub.

A source of water 31 of controllable temperature is also provided. It may take the form of a regulator adapted to receive both hot and cold water and to discharge water of a temperature selected on a dial (not shown).

Preferably, means are also provided for taking suction on fluids within and for discharging fluids into the various spaces. This may be a pump 32 which is capable of pumping both liquids and gaseous fluids in conjunction with an assembly of pipes and valves. Conveniently, an intake manifold 33 with four valves 34, 35, and 36, and 37 and a discharge manifold 40, with three valves 41, 42, and 43 may be used. In the illustrated embodiment, valve 34 is connected to the be-

3

tween-tubs chamber 29, thus making it possible for the pump 32 to take suction there. Valve 35 is connected to the annular space 18 around the lower end of the shaft 4a, thus making it possible for the pump to take suction through the shaft 4a from the top of the wash chamber 30 and when the sleeve 10 is down to take suction also from the bottom of the wash chamber 30. It should be observed however, that when the sleeve 10 is up, suction may be taken from the top of the wash chamber 30 above the level of water therein, thereby drawing a vacuum, without also taking water from the bottom of the tub.

Valve 36 may be connected to the source 31 of water of predetermined temperature, thereby facilitating the rapid use of water of low pressure.

Valve 41 in the discharge manifold may be connected to the between-tubs chamber 29 and valve 42 to a waste line. Similarly, valve 43 may be connected to the annular space 18 around the lower end of the shaft 4a, thereby making it possible for the pump to discharge into the shaft 4a, and into the top of the wash chamber 30 when the sleeve 10 is up. Other embodiments of the invention may so arrange the valves and openings that it will not be necessary to pass water through the center of the agitator shaft 4a.

Operation

The operation of this invention, and the processes thereof, can best be explained by running through typical wash cycles, rinse cycles, water extraction cycles, and dry cycles.

In the first stage of one possible wash cycle, soap and then clothes are placed in the wash chamber 30 through the opening in the top thereof, and the lid 2 is then secured, airtight, in the opening. With the sleeve 10 up, and all other valves closed, valves 35 and 41 are opened and the pump 32 started. A vacuum is drawn in the wash chamber 30 and a pressure of at least one atmosphere is present in the between-tubs chamber 29. Conveniently, more pressure may be obtained between tubs by opening valve 37 momentarily and allowing the pump to take suction on the open atmosphere and discharge additional air into the between-tubs chamber 29. A between-tubs pressure on the order of two or three atmospheres is acceptable for this step.

The flexible tub 28 will collapse around the clothes and compress them into a small space, and will make the wash chamber 30 itself as small as the particular load of clothes will permit. Then all other valves are closed and remain closed and valves 36 and 43 are opened. Water of the desired temperature is admitted to the pump which discharges the water under force through the shaft 4a against the top 2, thereby spraying the clothes and wetting them from the top as the tub fills. Since the wash chamber is no bigger than the space the clothes occupy, and since the water is admitted from above the clothes, the entire load of clothes is wet thoroughly and quickly with a small amount of water. This novel way of solving the problem of floating dry clothes is a significant contribution to the art.

When a sufficient amount of water has been admitted to wet the clothes—a significantly less amount than that required in other washers—the previously open valves are closed and valves 34, 35 and 42 are opened so that the pump 32 will draw a vacuum on the between-tubs chamber 29 and the wash chamber 30 through the openings 6 in the top of the shaft 4a, discharging

4

to a sewer line (not shown). A pump control (not shown) may be provided which will cause the pump to maintain the exact vacuum for maximum boiling at the desired temperature—175° F. for cottons, lower temperatures for more delicate fabrics—and a small amount of heat may be introduced into the machine by the heater 26, thus effecting active boiling from the very bottom of the wash chamber 30.

10 This boiling action at reduced pressures causes soap or other cleaning compound to pass quickly into solution, and since the amount of water present is small, effects a thorough saturation of all the clothes with soap.

After a short period of boiling the heavily saturated soap solution, valves 34, 35 and 42 are closed and valves 36 and 43 may be opened again until the proper amount of water for the second stage of the washing cycle, at least a half tub of water, has been admitted to the washing chamber 30. With valves 34, 35 and 42 re-opened, and other valves closed, washing by boiling agitation at controlled temperatures may be resumed.

When the clothes being washed are delicate or not very dirty, the first stage, i. e., boiling in heavily saturated soap solution, may be omitted. The boiling action provides ample agitation for washing silk stockings and similar articles. The innovation of using boiling action at controlled temperatures as a source of agitation, and the flexibility of a means for and method of washing which is adaptable for washing any materials from the most delicate to the most rugged in the same machine are most significant contributions to the art.

At the conclusion of the second stage boiling action, or in lieu thereof if such should be the desire of the operator, the third stage of the washing cycle is commenced. The motor (not shown) may be turned on and caused to activate the pinion 24 with an oscillating motion, thereby causing the agitator to oscillate. The use of this type of agitation is familiar to those skilled in this art. The use of this agitation simultaneously with boiling action is unknown to the present art, however, and it has been found that such combination effects improved and more rapid washing. The invention contemplates flexibility whereby the mechanical agitation can be used either alone, or in conjunction with boiling agitation.

Yet a fourth stage of the washing cycle is available for use in accordance with this invention, on clothes which demand it. The wash water may be pumped from the washing chamber 30 into the between-tubs chamber 29. The valves, pipe, and pump are of such size as to permit this operation to be a very rapid one. The flexible tub 28 is caused to squeeze the water through the clothes with great force, and a vacuum is drawn on the clothes when the water is removed. Then the water is returned to the wash chamber. It has been found that several repetitions of this type of hydraulic agitation, which impels quantities of water through the clothes with great force rather than just tumbling or agitating the clothes in water and which periodically draws the water and dirt and soap along with it from the very center of the fibers when a vacuum is drawn on the clothes, is most effective to remove stubborn dirt. Yet the operation is gentle on clothes and uses no extra water.

It is to be observed that the invention contemplates a washing process wherein three different types of washing agitation—boiling, mechanical

and hydraulic—may be used to best advantage, and further teaches apparatus whereby such combination of washing actions is possible. The degree of flexibility and adaptability of this invention for use on all clothes from the most delicate to the most rugged in one machine is, although long sought after, unknown to the prior art.

In order to simplify the explanation of this invention, no attempt has been made to show circuits, dials, etc., whereby the various choices of washing processes and temperatures may be made by simple dial selectors, but those skilled in the art will appreciate that this invention adapts itself to completely automatic operation by dial selectors.

When the clothes are washed satisfactorily, a choice of procedures for a water extracting cycle is available. A preferable choice includes a first and a second phase.

To perform the first phase, assuming the wash water to have been returned to the wash chamber 30, open valves 37 and 41 and discharge air into the between-tubs chamber 29 until a pressure on the order of several atmospheres is built up. In alternative embodiments tap water pressure may be used, but air pressure is preferable for use in conjunction with the second phase of this extraction cycle.

With the required pressure between tubs, close all previously open valves and open valves 35 and 42, thereby drawing a vacuum on the clothes while at the same time subjecting them to a squeezing action by the flexible tub 28 of several atmospheres. If the sleeve 10 is left up during the initial part of this operation, most of the wash water may be removed through the opening 6 at the top of the shaft 4a, thereby effecting removal of soap suds, dirt and scum from the top of the chamber without its passing through the clothes. When the washing chamber 30 is nearly dry, the sleeve 10 may be lowered so as to permit drainage of the last remaining water.

This phase solves the problem of some prior art machines which do not squeeze the clothes satisfactorily dry when used at high altitudes, and offers a further improvement over such washers wherever used by adapting a squeezing force of several times one atmosphere. This phase alone renders the clothes drier than any presently known extracting process or machine.

The second phase of the extracting process depends for its effectiveness upon the clothes being compressed into a solid mass without excessive air space by the action of the flexible tub 28 under force from the between-tubs pressure.

It has been found that substantial quantities of water can be extracted from clothes so compressed by forcing air through them. This is accomplished by opening the drain 3, valves 37 and 43, and discharging large quantities of air under pressure from the pump 32 into the top of the washing chamber 30 which has been forced into the contours of the wash load by the collapsing of the flexible tub 28. This second phase of the water extraction cycle is also a novel contribution to the art.

When the water extraction cycle has been completed, much less soap and water remains in the clothes than is left by conventional processes, thus making it possible to save rinse water and to complete the rinsing in a shorter time. Further, rinsing may be accomplished two or three times in the manner suggested by the first boiling phase of the wash cycle (the effective size

of the washing chamber being reduced) with the same amount of water normally required for one rinse. A desirable alternative rinse cycle may include rinsing with mechanical agitation as suggested in the third phase of the wash cycle, hereinbefore described. Any or all three types of agitation used in the wash cycles are, of course, available for rinsing, and the water extraction cycle following rinsing may include either or both phases of the water extraction cycle previously described with respect to wash water.

It is significant that the extracting cycle which is a part of this invention may be accomplished quietly and without vibration. The only machinery in operation is a pump which may be of a rotary and very quiet type.

This invention further contemplates a dry cycle in the same machine which is used for washing and rinsing, thereby eliminating the need for two separate machines in the home, and effecting great savings in cost. The top 2 is removed from the machine and a drying fluid of high volatility and high miscibility with water, such as alcohol, is poured onto the clothes. Preferably the clothes are again squeezed with all drains closed under a pressure on the order of three or four atmospheres. A suitable time must be allowed for the drying fluid to mix with the water. During this time heat is added to the clothes by the heater 26. If the clothes are cotton, they are brought up to a temperature of about 175° F. Lower temperatures are used for more delicate fabrics and for fabrics which dry more easily. Any liquid alcohol reaching the heater is flashed into vapor and moves back upward through the clothes. When the clothes, wet with alcohol or a similar fluid, are at the proper temperature, a vacuum is drawn on the wash chamber by pump 32 taking suction through valve 35 and discharging through valve 42, and causing residual alcohol-water mixture to boil away. The use of the second phase of the extracting cycle again at this point is beneficial.

The combined action of the drying fluid, the heat, the vacuum, and the passage of air through the clothes effect a rapid and complete drying of clothes in a period of time unheard of in drying cycles known to the prior art. Further, the drying fluid is a solvent for certain types of stains and also performs cleaning, sterilizing, and mildew inhibiting functions during the drying cycle. Only a small quantity of heat—an insignificant percentage of the amount used by clothes dryers known previously is required in this drying operation. The advantages of lower cost of operation of the drier, and of less heat dissipated into the surrounding space in which a housewife or other person must work are obvious, in addition to the great saving of time. Moreover, since the rinsing action of this invention is more complete, and less soap film and dirt remain in the clothes, and further as a result of the lack of need for bringing clothes even near a scorch temperature, there is no toasting and discoloration common to clothes washed and dried in present-day machines and by present processes.

It is also significant to observe that the invention, more flexible in itself than present washing processes and apparatus, is adaptable for more flexible control. More clothes may be added or some removed at any time by merely stopping the machine. There is a saving of soap since there is no need for a "soak period" with soap, as now required in most processes. The function of the soak period is accomplished in

the first stage of the wash cycle, but the soap is not lost—it is used also in the final stages of the washing cycle. Rinsing is made easier since, by the end of the last wash phase, the soap concentration in the fibres of the clothes has been reduced from the concentration effected in the first phase. This is brought about by the addition of more wash water during the wash cycle. There is no lint problem as is common with other washers and driers. Boiling of clothes during the rinsing has been found to effect greatly improved and more rapid rinsing.

The basic principles inherent in this invention are also adaptable for use in dishwashing, either in apparatus of somewhat simplified design, or in the apparatus disclosed and described herein. Preferably, any simplified design should include a wash chamber of variable size so that small loads of dishes may be washed with a small amount of water and cleaning compound. Dishes may be placed at random in the wash chamber 30, and water is admitted to the wash chamber 30 until the dishes are immersed by opening valves 36 and 43. Boiling agitation substantially as described in stage two of the clothes wash cycle may then be used in alternation with the step of subjecting the wash chamber to pressure by opening valves 37 and 43 with other valves closed.

Water under pressure will penetrate dried egg yolk, grease, and other foreign matter on dishes and kitchen utensils; upon sudden release of pressure and drawing of vacuum, the water will bubble from the surface of the dirty article taking dirt and grease along with it, thereby effecting a better cleansing of dishes and kitchen ware than is accomplished by water spray methods common to the art. Drying of dishes and other utensils may be accomplished by heat and vacuum boiling, without collapsing the flexible tub. It is significant to note that this invention contemplates single apparatus which may be used for washing both clothes and dishes.

Washing liquids other than water may be used. Other modifications may be made without departure from the scope of this invention. The above description, therefore, is to be construed as illustrative only, and is not to be construed in any limiting sense.

I claim:

1. In a washing machine including an outside tub with an agitator therein, the combination of a flexible tub positioned within said outside tub and forming a washing chamber containing said agitator, a valve extending into the bottom portion of said washing chamber and providing an opening communicable therewith, the top of said agitator having an opening communicating with said washing chamber, said agitator having a passageway therethrough communicating with said top opening and with said valve opening in the bottom of said washing chamber, a pump with suction and discharge lines, said suction line being connected through a valve to said agitator and communicating with said top opening in the agitator, said suction line being further connected through

a valve to said outside tub in back of said flexible tub, said suction line being further connected to a source of water of controllable temperature, said discharge line being connected through a valve to said outside tub in back of said flexible tub, said discharge line being further connected through a valve to said agitator and communicating with said top opening in the agitator, said discharge line being adapted for a still further connection through a valve to a waste line, and a heater positioned in the bottom portion of said washing chamber.

2. In a washing machine including an outside tub with means for agitating fluid therein, a flexible tub secured within said outside tub and enclosing a wash chamber and forming a between-tubs chamber, pump means adapted to take suction from a top portion and from a bottom portion of said wash chamber, and from the between-tubs chamber, and adapted to discharge to a waste line, and means for placing fluid under pressure in the between-tubs chamber.

3. In a washing machine including an outside tub with means for agitating fluid therein, a flexible tub positioned within said outside tub and forming a washing chamber containing said agitating means, and pump means adapted to take suction from a top portion and from a bottom portion of said washing chamber, from said outside tub in back of said flexible tub, and from a source of water of controllable temperature, and further adapted to discharge to a waste line, to said outside tub in back of said flexible tub, and to the washing chamber.

ILLIFF DAVID RICHARDSON.
